Primary Examiner — April Rivas*Assistant Examiner* — Jillian Mazzola(74) *Attorney, Agent, or Firm* — McGarry Bair PC(57) **CLAIM**

The ornamental design for a carrier, as shown and described.

DESCRIPTION

FIG. 1 is a top perspective view of a carrier, showing my new design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken lines depict portions of the carrier that form no part of the claimed design. Unshaded portions adjacent solid lines or broken lines form no part of the claimed design.

1 Claim, 4 Drawing Sheets(56)
